FIG. 7.

INVENTOR,

By Otto Carlborg.
Geo. Remington Atty.

UNITED STATES PATENT OFFICE.

OTTO CARLBORG, OF PROVIDENCE, RHODE ISLAND.

MAGNETO-ELECTRIC IGNITER DEVICE FOR EXPLOSIVE-ENGINES.

No. 878,935.

Specification of Letters Patent.

Patented Feb. 11, 1908.

Application filed March 11, 1907. Serial No. 361,636.

To all whom it may concern:

Be it known that I, OTTO CARLBORG, a citizen of the United States of America, and a resident of Providence, in the county of Providence and State of Rhode Island, have invented certain new and useful Improvements in Magneto-Electric Igniter Devices for Explosive-Engines, of which the following is a specification.

10 My invention relates to magneto-electric igniters for explosive-engines, the device being of the general type or class in which the armatures of the magnetos employed have an intermittent or oscillatory movement.

15 The object I have in view is to provide a magneto of the class referred to with improved simple and comparatively inexpensive means for positively oscillating the armature in a uniform manner in both directions.

20 By means of my invention, which includes a continuously revoluble novel track-cam, a much quicker and more uniform angular movement of the armature is attained; the 25 strength of the current produced by and during each movement of the armature in either direction is substantially invariable; the armature driven mechanism and said cam may be rotated at a reduced rate of speed, while at

30 the same time increasing that of the armature; the latter may be oscillated a number of times, say four, and in a positive manner; per revolution of its actuating means; a quicker action is imparted to the armature, 35 the same being effected by a short angular movement of the driving-gear or cam; no springs whatever are employed; it is practically noiseless and the degree of working friction is greatly reduced; and the cam may

40 be driven by any shaft or other suitable means arranged to break the magnetic field at the proper time, or, in other words the construction is such that a high armature speed is attained with a much slower rotary 45 cam movement.

In the accompanying sheet of drawings, Figure 1 represents a front end elevation of a magneto embodying my improvement. Fig. 2 represents a corresponding side elevation. 50 Fig. 3 is a corresponding top plan view. Fig. 4 is an end elevation, in partial section, the driving-gear being omitted so as to show the relative arrangement of the armature, field-pieces, etc. Fig. 5 is a front elevation, in enlarged scale, a portion of the cam being 55 broken away, showing the cam-path and the

relation of the armature-crank thereto. Fig. 6 represents a rear view of the cam itself, and Fig. 7 is a vertical sectional view, taken on line x of Fig. 6, showing the manner of constructing the cam.

The following is a more detailed description of my invention, and including the correlated parts or elements.

The magneto as a whole is designated A in 65 the drawings. I would state here that the usual non-magnetic base a , the several permanent magnets b , the oppositely disposed fixed pole-pieces or field-magnets f , the armature B, its shaft c and the rear conductor 70 member m , insulated at m' , from which the generated current flows via the wire t to a suitable timing device, are or may be constructed and arranged in any well-known manner, and I therefore make no specific 75 claim to said parts herewith.

My invention resides, essentially, in the novel revoluble disk-like cam member C operatively connected with and adapted in its movements to intermittently oscillate the 80 armature in a positive manner. To the front end of the armature shaft c is secured a short crank d having a pin d' carrying a roll r adapted to the groove of the said cam, about to be described.

As drawn, the cam C is revoluble on a stud a' fixed in a front extension a' of the said base member a ; the location of the stud with respect to the armature shaft being such that the major and minor radii of the path D of 90 the cam positively determine or limit the degree of vibration or angular movements of the armature. The said cam has a disk-like form, its hub being bored to turn freely on the fixed stud or support and to be driven by 95 a gear g , or other analogous device, secured thereto, as clearly indicated in the drawings.

The casing or body portion n of the cam may be made of cast iron, and having a rearwardly extending peripheral rim n' integral 100 therewith. The said cam-groove proper, D, is formed in the rear face of the cam. In lieu of cutting away the stock to form the groove the latter may be produced, as represented in the drawings, by a plurality of suitably 105 shaped thin flat plates u of non-metallic material, as for example fibroid, alternating with similarly shaped thin flat sheets or plates v of metal, as brass or steel. See Fig. 7. The several pieces of sheet stock are 110 superposed in and practically fill the annular space formed between the rim and hub por-

tions of the cam and are removably secured in position by suitably disposed screws s^1 passing transversely through the members n , u and v and tapped into correspondingly shaped laterally movable metal fastening-plates h h^1 . As thus constructed the plates u and v interposed between the casing part n and the said backing members are all adapted to be rigidly clamped together.

In Figs. 5 and 6 the continuous groove or path D of the cam is represented as being divided into four curved idle sections, the length of each arc being about 90° . The two outer sections, e e^1 , are oppositely disposed and are described from the cam's center by the longer radius, the other two sections, e^1 e^2 , are also oppositely arranged with respect to each other and are located at right angles to and being disposed in a circle concentric with the first-named sections, and being described by the shorter radius, all the sections being in one common plane. The adjacent ends of each of the sections e and e^1 terminate in a straight section, e^2 ; each of the latter when in use constituting the operative portion of the cam, its angular length being about one-fifteenth of the cam's circumference, as indicated at z in Fig. 6. It will be seen that the two sections e^2 on each side of the cam are or may be in alinement and also parallel with the corresponding section, e^2 , on the opposite half of the cam.

Any suitable means may be employed for driving the improved magneto A. In the drawing a shaft s carrying a gear g^1 is adapted to be rotated in any well-known manner relatively to the speed of the engine, thereby positively rotating the gear g , meshing with gear g^1 , and the cam C secured thereto.

Now assuming the magneto A to be electrically connected (in any well-known manner, or as indicated in Fig. 3) by a conductor t leading from the armature-shaft to a suitable timing device T, the latter in turn being connected to the spark-plugs of the cylinders of an engine E, and having a return or "ground" conductor t^1 connected with the engine and magneto, all arranged and adapted for operation substantially as usual; and further assuming the cam C of the magneto to be continuously revolving in the arrow-direction at the desired speed, the armature B and its crank d at the instant 55 then being stationary and in the position represented say in Fig. 5, the manner of operation of the cam, &c., may be described as follows: The short angular movement (z , Fig. 6) of the cam, being the length of each working section e^2 , will in coöperation with the crank-pin and roll mounted in the cam-groove quickly vibrate the crank ahead or toward the right to the central dotted line position d^2 , indicated in Fig. 5, thereby correspondingly rotating the armature and

breaking the magnetic circuit between the poles, the resulting action being utilized, in coöperation with the means indicated in Fig. 3, to produce an electric spark for igniting the charge of gas in the cylinder of the engine. The armature remains idle or stationary while the roll r is guided in the corresponding outer concentric arc section e of the revolving cam; the latter in its movement through the next angular distance z , 75 corresponding with that working section e^2 , causes the crank and its armature to quickly swing back to the left position thus again breaking the magnetic circuit. The armature now remains idle while the cam is revolving through the succeeding inner concentric arc section e^1 and until the next working section, e^2 , is reached; the angular movement z of the cam then instantly swings the crank ahead again back to the right as before described, thereby again breaking the magnetic circuit, the armature meanwhile remaining idle while the cam moves through the succeeding outer section e until the roll engages the next working section, the movement z , as before stated, then swinging the crank to the left to again break the circuit. The armature and its connected parts now remain stationary or idle during the cam's movement through the next inner concentric arc section e^1 until the base of the succeeding section e^2 is engaged by the roll-carrying pin of the crank member d , thus completing one revolution of the cam, the relation of the parts then appearing as represented in Fig. 5. The operation just described is continuously repeated while the engine remains in action.

It will be apparent that the action of the continuously revoluble cam causes the armature to be swing quickly and positively on its axis four times and at regular intervals during each revolution of the cam, the armature being idle or stationary during the remainder of the cam's said movement. By means of my improved construction and arrangement the magneto-electric current may be generated and utilized with greater efficiency; the driving-gear mechanism may be rotated at a reduced rate of speed while at the same time materially increasing the speed of the intermittently movable armature; the cam action is practically noiseless and is readily accessible for inspection, lubrication, &c., and the cam and armature are adapted to run in either direction with equal efficiency and at any desired rate of speed.

What I claim as my invention, and desire to secure by United States Letters Patent, is:—

1. In a magneto-electric igniter device or magneto for explosive engines, the combination with permanent magnets and field-pieces, and an armature operatively located with respect thereto, of a continuously rev-

oluble driving member having a continuous cam-shaped groove or path, and a crank secured to the armature and coöperating with said grooved member for imparting a plurality of intermittent oscillatory movements to the armature to produce a corresponding number of ignition sparks during each revolution of the driving member.

2. In a magneto device of the character described, the combination with the movable armature thereof and a crank member secured thereto, of a continuously revoluble driving disk having a plurality of evenly spaced divisions or members adapted to be 15 operatively engaged by said crank in a suc-

cessive manner, constructed and arranged so that when in use the armature will be vibrated quickly and intermittently a short angular distance a corresponding number of times during each revolution of said disk, 20 the armature remaining in an idle or stationary position immediately succeeding each vibratory movement.

Signed at Providence, R. I., this 7th day of March, 1907.

OTTO CARLBORG.
